UNITED STATES PATENT OFFICE

2,605,617

COLLAPSIBLE CABINET REFRIGERATOR

James B. Replogle, Waukegan, Ill.

Application March 3, 1949, Serial No. 79,460

12 Claims. (Cl. 62—89)

1

This invention relates to improvements in a refrigerator for the storing of foods and other perishables, the invention being highly desirable for use in connection with relatively large sized refrigerators for larger homes, commercial establishments, and the like, although the invention will have other uses and purposes as will be apparent to one skilled in the art.

In the past, many and various types of refrigerators for the storage of foods and other perishables have been designed. Extreme difficulty has been experienced, however, in the placing of a relatively large sized refrigerator in a commercial establishment, a large home, or some similar location, due to the small entrances provided to the building. Frequently a door and adjacent portion of a wall would have to be removed and then replaced after the refrigerator had been positioned within the building, unless the refrigerator was actually constructed inside the building, the latter procedure, of course, being objectionably expensive. Great difficulty has also been experienced in the past not only in maintaining the temperature in the storage compartment of a refrigerator substantially constant, but also in maintaining that temperature substantially uniform throughout the entire storage compartment.

With the foregoing in mind, it is an important object of the instant invention to provide a complete refrigerator cabinet, exclusive of a door or doors, which is foldable into a compact layer-on-layer form thereby facilitating handling and shipping.

It is also an object of this invention to provide a refrigerator, complete except for a door or doors, which may be manufactured even extra large and is readily collapsible to permit ready and easy entrance and exit through the normal opening to a building.

It is also a feature of this invention to provide a refrigerator in which the refrigerating mechanism itself is disposed entirely outside the storage cabinet, where the mechanism is readily accessible and the full storage space inside the cabinet is usable.

Still another feature of this invention resides in the provision of a refrigerator of the mechanical type in which no moving parts are incorporated anywhere inside the cabinet, and there is nothing associated with the cabinet to become out of order during normal usage.

It is also an object of this invention to provide a refrigerator, which may be made of substantially any desirable size, and in which the temperature is not only maintained substantially constant, but substantially uniform throughout the

2

entire storage compartment, regardless of the size of that storage compartment.

A further feature of the invention resides in the provision of a refrigerator in which the bottom, top, back, and side walls of the storage compartment are directly chilled over substantially their entire surface.

It is also a feature of the invention to provide a refrigerator in which a cooling or convection fluid circulates through the walls of the storage compartment.

The instant invention also seeks the provision of a highly efficient refrigerator wherein a convection fluid circulates over the outer face of the inside lining or skin of the storage compartment, and the circulation space in the walls is baffled at judicious locations to insure an even heat transfer over substantially the entire wall surface.

An important feature of the instant invention is the provision of a refrigerator, which may be made in substantially any desirable size, and which is readily foldable or collapsible to permit easy entrance and exit through normal openings to a building, and wherein a convection fluid circulates through a space in the walls of the storage compartment, and the fluid passes from wall to wall through the hinges joining the respective walls together.

Still another object of the instant invention is the provision of a new type hinge construction capable of passing a fluid therethrough from one to the other of the parts pivotally connected by the hinge.

While some of the more salient features, characteristics and advantages of the instant invention have been above pointed out, others will become apparent from the following disclosures, taken in conjunction with the accompanying drawings, in which:

Figure 1 is a pictorial view of a refrigerator, less a door or doors, embodying principles of the instant invention, showing the same in folded or collapsed form.

Figure 2 is also a pictorial view of the structure of Fig. 1 showing the same in partially unfolded condition;

Figure 3 is a pictorial view of the structure of Fig. 1 showing the same with doors attached and set up in position for use;

Figure 4 is a greatly enlarged fragmentary vertical sectional view taken substantially as indicated by the line IV—IV of Fig. 3, looking in the direction of the arrows, and illustrating the arrangement of an inside hinge with respect to the adjacent walls joined by that hinge;

Figure 5 is a view similar in character to Fig. 4,

but a plan section taken substantially as indicated by the line V—V of Fig. 3, illustrating the association of an outside hinge with adjacent walls;

Figure 6 is an enlarged view of an outside hinge spread open, with the central portion shown in section;

Figure 7 is a diagrammatic view indicating very diagrammatically the flow of convection fluid through the walls of the refrigerator;

Figure 8 is an enlarged fragmentary vertical sectional view taken substantially as indicated by the line VIII—VIII of Fig. 3, indicating the means for securing adjacent walls together; and

Figure 9 is a fragmentary diagrammatic view illustrating a refrigerator cooling mechanism in elevation outside the refrigerator cabinet, and showing the cabinet in plan section to indicate the arrangement by which the convection fluid is maintained in a cold condition.

As shown on the drawings:

The illustrated embodiment of this invention embodies a refrigerator cabinet, preferably made of six or seven panels, depending upon whether one or two doors are used. Prior to delivery, five panels are connected together, the doors not being attached until the refrigerator is mounted in its location for use.

As seen in Figs. 1, 2 and 3, the refrigerator cabinet, exclusive of the door or doors, includes a back panel or wall 1, a top panel 2, a bottom panel 3, and a pair of oppositely disposed side or end panels 4 and 5. Each of these panels is preferably provided with a surrounding edge portion in the form of substantially a 45° bevel so that each panel may readily be disposed at right angles to an adjacent panel and there will be a tight and uniform fit between the panel edges. Such bevel arrangement may be indicated at 6 in Figs. 1 and 2, and it will be noted that all bevels are preferably sloping inwardly.

The top and bottom panels 2 and 3 are preferably secured to the back or rear panel 1, each by one or more inside hinges 7, there being two such hinges in the illustrated showing for joining each of the other panels to the back panel. The side panels 4 and 5 are similarly connected to the rear panel 1, but in this case outside hinges 8 are employed. Thus, complete collapsing of the cabinet may be had by folding the top and bottom panels 2 and 3 over one face of the rear panel 1, and folding the side panels 4 and 5 over the other face of the rear panel, as clearly seen in Fig. 1. When in such collapsed or folded condition, it is obvious that the refrigerator cabinet may be readily and easily passed through substantially any entrance opening to a building, whereas it would be impossible to pass the cabinet in box-like formation ready for use through such an opening. As will be noted from the showing in Figs. 1 and 2, the cabinet may readily be constructed with each of the top, bottom, and side panels of substantially half the size of the rear panel.

When it is desired to assemble the cabinet for use, it is a simple expedient to set the folded cabinet of Fig. 1 upright, drop the bottom panel 3, raise the top panel 2, and forwardly fold the side panels 4 and 5 into intimate edge engagement with the other panels. The panels may readily be secured in their useful position by means to be later described. After the assembly of the cabinet itself, one or more doors 9 may easily be added, and in the illustrated instance I have elected to show two such doors, although in many cases only one door is preferred.

If so desired, suitable feet 10 may be provided on the underside of the bottom panel 3.

With reference now to Fig. 8, it will be seen that two of the walls, preferably the top and bottom walls 2 and 3, are provided with open bottom sockets 11 adjacent each corner or wherever else may be deemed desirable. These sockets when the panel is disposed at right angles to an adjacent side panel merge with the socket 12 mounted in the side panel so that a bolt or stud 13 may be threadedly engaged in both sockets, thus firmly uniting the panels at their adjacent beveled edges.

With reference more particularly to Figs. 4 and 5, it will be seen that each panel or wall comprises an outer skin 14, preferably of sheet metal, a false inner lining or skin 15, and an actual inner lining or skin 16. The inner linings 15 and 16 are spaced apart to provide a cavity or jacket 17 therebetween through which a convection liquid may circulate. Between the false inner lining 15 and the outer skin 14 suitable insulation 18 is provided. The insulation may be of non-rigid, semi-rigid or rigid construction, and, as stated above, the outer skin 14 is preferably of relatively rigid material such as sheet metal to withstand abuse, and particularly so in case the insulation is of the non-rigid type. Both the outer skin 14 and the inner skin or lining 16 preferably have their margins turned inwardly to partially extend across the bevel face of each wall and these margins are joined by a thermally non-conductive strip or panel 19 which may suitably be made of plastic. As seen in Fig. 4, the inner lining 16 is preferably shaped as indicated at 20 to smoothly accommodate the leaves and knuckle arrangement of an inside hinge 7. With reference to Fig. 5 it will be seen that the outer skin 14 is shaped inwardly as at 21 to accommodate the leaves of an outer hinge 8. It will be understood, of course, that the inner lining 16 may be enameled, polished, or otherwise provided with a desirable surface.

Again looking at Fig. 5, it will be noted that in order to establish communication between the fluid jacket 17 of one wall, and the fluid jacket 17 of an adjacent wall, passages are provided through the walls to the respective hinge in the case of an outside hinge 8. It will be noted from this showing that the wall 1 is provided with a tube 22 communicating at one end with the respective jacket 17, extending through the insulation 18, and communicating at the other end through the outer skin 14 with a passage 22a in the hinge. In similar fashion the adjacent side or end wall 4 is provided with a tube 23 communicating at its inner end with the respective jacket 17 and at its outer end with another passage 23a in the same hinge. Since each hinge is firmly attached to adjacent walls in the usual manner, there is no opportunity for the passage through the wall becoming out of alignment with the corresponding passage in the hinge.

In Fig. 6 I have illustrated an outside hinge 8 which includes a pair of opposed leaves 25 and 26. The leaf 25 is provided with an upper knuckle 27 and a lower knuckle 28 spaced therefrom. The leaf 26 is provided with a single intermediate knuckle 29 which extends between the knuckles 27 and 28 of the leaf 25. The passage 23a of the hinge extends through the knuckle 27 into communication with an interior bore 30 in direct communication with an interior bore 31 in the knuckle 29, and the aforesaid passage 22a communicates with the lower part of the bore 31. The adjacent

ends of the knuckles 27 and 29 are shaped to provide a conical seat therebetween as indicated at 32 to insure a fluid tight seal. The lower knuckle 28 is internally threaded to accommodate a bolt 33, the inner end of which bears against the lower part of the knuckle 29 as indicated at 34. When the bolt 33 is loosened, the leaves of the hinge are free to pivot relatively to each other. However, when the bolt is tightened, the leaves are locked in their relative position and there is a fluid tight seal between the passage in the knuckle 27 and the passage in the knuckle 29. It will be understood, of course, that once the refrigerator is assembled, the bolt 33 may be positively tightened in position because thereafter the adjacent panels or walls of the cabinet are fixed in position and do not move relatively to each other.

With this type of hinge, it will be seen that convection fluid occupying the jacket 11 of the rear panel 1 may pass through the tube 22, the lateral passage 22a of the hinge, the central passages 31 and 33, the lateral passage 23a, and through the tube 23 into the jacket 11 of the next adjacent panel 4.

In respect to an inside hinge 7, the general structure is substantially identical with the outside hinge just above described, with the exception that the lateral passageways 35 and 36 of the hinge are disposed at a slightly different degree of angularity relatively to each other, as seen in Fig. 4. These passages 35 and 36 need only communicate with a suitable opening through the adjacent portions of the inside lining 6 on the respective panel member.

With reference now to Figs. 7 and 9, it will be noted that there are a pair of adjacent tubes 37 and 38 extending laterally through the rear wall 1 into communication with the jacket 11. The outer ends of these tubes are provided with flanges 39 for connection with suitable conduits. The fluid passing through the jacket of the respective walls may enter through the tube 37 and exit through the tube 38, passing through one panel and then the other by way of the above described hinges during its course of travel through the entire cabinet. In order to insure an even distribution of the fluid, the respective jackets 11 are preferably baffled. To this end, the jacket of the rear panel is divided into substantially four quarters by a baffle 40 in the form of a Greek cross. Each arm of this cross, as seen clearly in Fig. 7, extends completely to the jacket wall. Each of the panels 2, 3, 4, and 5, is provided with one or more baffles, in the illustrated instance, a central baffle 41 being shown, and these baffles stop short of the outer wall of the respective jacket. In addition, the rear panel 1 is provided with an extra baffle 42 disposed between the inlet 37 and the outlet 38 to block off any direct communication therebetween.

This baffle arrangement provides a complete circulatory system through the jackets of each wall of the cabinet as very diagrammatically indicated by the arrow chain 43 in Fig. 7. It will be noted that the convection fluid may enter the port 37 into the jacket of the rear panel outside the baffle 42, pass through the adjacent hinge 8 into the panel or wall 4, proceed around the baffle 41, and through the next outside hinge 8 into another quarter portion of the rear wall 1, through an inside hinge 7 to the jacket of the wall 2, around the corresponding baffle 41 and through the other inside hinge 7 into another quarter portion of the rear panel 1, and so on until the con-

vection fluid finally exits through the port 38. The convection fluid in each case will fill substantially the entire jacket space due to the pressure thereon, and will not merely follow the rather meager path indicated by the arrow chain 43. It will be noted that each time the fluid passes through a top, bottom or side wall, it passes through a portion of the rear wall before reaching the next top, bottom or side wall. With this arrangement, all the inside walls of the cabinet are maintained at substantially a constant temperature.

Any suitable form of convection fluid may be utilized, and by way of example and not by way of limitation, I may mention that water with an ethylene glycol content sufficient to prevent freezing is quite satisfactory.

As indicated clearly in Fig. 9, the actual refrigerating mechanism is entirely outside the cabinet. This mechanism may be standard mechanical refrigeration means embodying a compressor 44, a condenser 45, an evaporator 46, an expansion valve or other restrictor 47 in the high pressure line coming from the condenser and leading toward the evaporator, and a low pressure return line 48 from the evaporator back to the compressor. This is a closed system and any suitable refrigerant may be used therein.

A jacket 49 is associated in heat exchange relationship with the evaporator 46 of the refrigerating unit. This jacket is connected by a conduit 50 to a pump 51 which is in turn connected through a conduit 52 with the inlet port 37 to the cabinet. A conduit 53 connects the outlet port of the cabinet to the far side of the jacket 49. The convection fluid is contained in the jacket 49, the cabinet, and the connections therebetween and is forced to flow through the walls of the cabinet in the manner above described by the pump 51. Preferably the pump 51 is so designed as to use a minimum quantity of energy, and operate continuously. Any suitable thermostat control may be arranged for the refrigerating unit so that this unit will start and stop in accordance with the temperature of the convection fluid in the jacket 49, thereby providing a very precise temperature control. It will be noted that with this arrangement, the difference of temperature of the convection fluid at the inlet port 37 from the temperature of the same fluid at the outlet port 38 of the cabinet may be very easily maintained within 1°. Accordingly, the temperature throughout the inside of the cabinet is substantially constant and substantially uniform throughout the entire storage space.

From the foregoing, it is apparent that I have provided a novel refrigerator cabinet of collapsible form, which may be manufactured in substantially any size, and which may readily and easily be brought into or removed from a building through the ordinary entrances.

It will also be noted that with the instant invention, wherein a convection fluid passes directly through the walls of the cabinet, the temperature is maintained constant and substantially uniform throughout the entire storage space, and the entire storage space is usable in that the refrigerating mechanism is totally outside the cabinet. Further, the structure is economical to manufacture, and extremely long lived because there are no parts to get out of order, and if necessary the refrigerating unit may be repaired and replaced at will without any work being done on the cabinet whatever.

It will be further noted that the entire struc-

ture is easily set up in position, the adjacent panels secured together, the hinges locked in place, and it is a simple expedient to then provide the convection fluid. With a sealed in system, that fluid need never be replaced.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. In a collapsible refrigerator cabinet, a rear wall, opposed top and bottom walls, opposed end walls, inside hinges connecting one pair of opposed walls to said rear wall, and outside hinges connecting the other pair of opposed walls to said rear wall, whereby said pairs of opposed walls may be folded over opposite faces of said rear wall.

2. In a collapsible refrigerator cabinet, a plurality of wall panels, hinges connecting adjacent panels together, each panel having an edge in the form of a bevel, and locking means associated with said hinges to secure them in fixed position when said panels are unfolded to cabinet form.

3. In a refrigerator cabinet, a pair of adjacent walls, a pair of hinges connecting said walls, each said wall having a convection fluid jacket therein, said hinges having passages therethrough, each said wall having communications between the respective jacket and said hinges whereby fluid may enter a jacket through one hinge and exit through the other, and baffle means in each jacket to cause the convection fluid to follow a tortuous path through the jacket.

4. In a refrigerator cabinet, a rear wall, and four side walls, a pair of hinges connecting each side wall to said rear wall, each said wall having a convection fluid jacket adjacent the lining thereof, said hinges having fluid passages therethrough, each said wall having means therein to establish communication between the respective jacket and the adjacent hinge means, and baffle means in said walls arranged to provide a tortuous path for convection fluid through said jackets, the fluid entering each side wall through one hinge and exiting through the other passing through a portion of said rear wall between adjacent side walls.

5. In combination, a collapsible refrigerator cabinet including a plurality of separate hollow walls hinged together to form a box-like structure, means establishing communication between the hollows of adjacent walls, and means external of said cabinet to pump a convection fluid through said walls.

6. In combination, a foldable refrigerator cabinet including a plurality of separate hollow walls pivotally connected to form a box-like structure, means establishing communication between the hollows of adjacent walls, baffles in the hollows of said walls to provide a tortuous path for convection fluid, and means to pump a convection fluid successively through said walls.

7. In combination, a foldable refrigerator cabinet including a plurality of separate hollow walls pivotally connected to form a box-like structure, means establishing communication between the hollows of adjacent walls, a refrigeration unit outside said cabinet and including an evaporator, a jacket in heat exchange relationship with said evaporator, and a closed convection fluid circuit

including said hollow walls, said jacket and a pump.

8. A hinge arranged to pass fluid therethrough, including a leaf having spaced knuckles thereon, a leaf having an intermediate knuckle thereon for disposition between said spaced knuckles, one of said spaced knuckles having a longitudinal passage therein with a lateral passage communicating therewith, said intermediate knuckle having similar passages therein with the lateral passage at an angle to that of said one spaced knuckle, said longitudinal passages being in alignment, said one spaced knuckle and said intermediate knuckle having a conical seat therebetween, and a bolt threaded through the other spaced knuckle to bear against said intermediate knuckle and lock the hinge with said conical seat establishing a fluidtight seal.

9. A hinge arranged to pass fluid therethrough, including a pair of leaves, a knuckle on each leaf, each knuckle having a lateral passage and a longitudinal passage in communication, and means to lock said knuckles with said longitudinal passages in alignment and a fluidtight seal therebetween.

10. In a refrigerator cabinet, a rear wall, four side walls connected to each side of said rear wall, means forming a jacket for convection fluid adjacent the inner face of each said wall, the jackets in said four side walls each communicating twice with the jacket of said rear wall, and baffle means in said rear wall jacket to cause the convection fluid to pass through each side wall jacket in turn but through a portion of the rear wall jacket between successive side wall jackets.

11. In a refrigerator cabinet, a rear wall, four side walls connected to each side of said rear wall, means forming a jacket for convection fluid adjacent the inner face of each said wall, the jackets in said four side walls each communicating twice with the jacket of said rear wall, baffle means in said rear wall jacket to cause the convection fluid to pass through each side wall jacket in turn but through a portion of the rear wall jacket between successive side wall jackets, and baffle means in each side wall jacket to cause the fluid to follow a tortuous path therethrough.

12. In a collapsible refrigerator cabinet, a rear wall, opposed top and bottom walls, opposed end walls, inside hinges connecting one pair of opposed walls to said rear wall, outside hinges connecting the other pair of opposed walls to said rear wall, whereby said pairs of opposed walls may be folded over opposite faces of said rear wall, and means forming a jacket for a convection fluid in each said wall adjacent the inner face thereof, said hinges being passaged to establish communication between the rear wall and said side walls.

JAMES B. REPLOGLE.
